UNITED STATES PATENT OFFICE.

MILLARD F. COX, OF LOUISVILLE, KENTUCKY, ASSIGNOR TO UNION METAL PRODUCTS COMPANY, OF CHICAGO, ILLINOIS, A CORPORATION OF DELAWARE.

RELEASE RIGGING FOR RAILWAY-CAR COUPLERS.

Application filed October 26, 1921. Serial No. 510,479.

To all whom it may concern:

Be it known that I, MILLARD F. Cox, a citizen of the United States, residing in Louisville, in the county of Jefferson and State of Kentucky, have invented new and useful Improvements in Release Rigging for Railway-Car Couplers, of which the following is a specification.

This invention relates to improvements in release rigging for railway car couplers and more particularly to a new and novel form of pin lifting link.

It is an object of this invention to provide a flexible pin lifting link between the car coupler lock pin and the crank arm of the rotatable operating rod of usual construction, which link is of simple form, positive in operation, efficient in service and complies with the requirements of the safety application rules of the Interstate Commerce Commission.

A great many cars in the past have been equipped with the rotatable operating rod having a crank arm connected to the car coupler lock pin by a chain and clevis, which now does not comply with the Interstate Commerce Commission rules, and it is an object of this invention to provide a link that may be readily applied to this type of release rigging and substituted for the chain and clevis or use with new operating parts.

This improved link may be called a slip link as it is made in two parts, each of which is undetachable when applied to the eyes in the crank arm and lock pin respectively and slide over each other so that the link is self adjusting in service during draft and buffing or curving.

While the preferred form of this invention is illustrated upon the accompanying sheets of drawings, yet it is to be understood that minor detail changes may be made without departing from the scope thereof.

In the drawings:

Fig. 1 is a view in side elevation of the end portion of a freight car to which this improved slip link has been applied, indicating in dotted lines the extreme upward position in lifting the locking pin to unlock the car coupler.

Fig. 2 is an enlarged detail view in front elevation of one member of one part of the slip link.

Fig. 3 is a view in side elevation of Fig. 2.

Fig. 4 is a top plan view of Fig. 2. 55

Figs. 5, 6, and 7 are views similar to Figs. 2, 3 and 4 respectively of the other member of this part of the slip link.

Fig. 8 is a view in side elevation illustrating the application of this slip link to the 60 crank arm coupler lock pin.

Fig. 9 is a view in front elevation of Fig. 8.

As illustrated in Fig. 1, the car end 1, end sill 2, striking casting 3, coupler head 4, 65 coupler lock pin 5, rotatable operating rod 6 with crank arm 7 and operating handle 8 are all of usual construction.

The slip link contemplated in this invention is best illustrated in Figs. 1, 8 and 9 70 in which the link is shown to be formed in two parts of two members each. The members 10 and 11 of the upper part are formed with their upper ends passing through the eye 12 of the crank arm 7 and the members 12 and 13 of the lower part with their lower ends passing through the eye 15 of the coupler lock pin 5. The adjacent ends 16 and 17 of both parts are bent at right angles to their respective bodies and then bent to completely enclose with sliding contact the adjacent body of the other member so that the end of the member 10 embraces the body of member 12 with the end of member 11 embracing the body of member 13 and thereby 85 forming a slip connection between the upper and lower parts of the link between the crank arm and the lock pin which will allow the link to contract or expand during draft or buffing without raising the lock pin. 90

The ends of the upper and lower parts adapted to pass through the eyes of the crank arm and lock pin are similarly formed and each bent in the form of an eye or full circles of equal radii with the termination of each end adjacent its respective body and the diameter of such dimension as to allow full play of the part in the eye of the crank and pin respectively. As shown in Figs. 2, 3, 4 and 8 the member 11 is throughout the 100 curved portion reduced in thickness, as shown by the numeral 18, while the curved member 12 of that part is slotted, as indicated by the numeral 19 with the slot of such dimensions as to receive the reduced portion 18, as shown in Fig. 8. 105

The link is preferably made of tough mild steel and the curved portions are originally left open wide enough to take the end of the crank arm and lock pin and be inserted through the eyes thereof and be closed cold, as shown in Fig. 9, without fracture. It is readily seen that the interlocking eyes of the members of each part reinforce the respective members and the operation of attaching them to the crank arm and pin is extremely simple like applying a split link to a chain or a key to a key ring.

Fig. 1 illustrates the locked position of the coupler head with the release rigging in normal position. From the above description and other views of the drawings it is readily seen that this link may adapt itself to any of the positions of the coupler head in service without disturbing the normal position of the lock pin. By lifting on the operating rod handle 8 the crank arm 7 is raised which will first bring the embracing ends 16 and 17 of the parts of the link in contact and then through the link lift the lock pin to uncouple the car, as shown in dotted lines in Fig. 1, and with the lock pin in locked set position the parts slip over each other so that the crank arm may return

to its normal horizontal position with the operating handle adjacent and parallel to the end sill.

What I claim is:

1. In a car coupler release rigging, a pin lifting link formed of two parts adapted to slide over each other, each respective part formed of two independent members, the adjacent ends of each set of members having a sliding connection with the body of the other part, and the opposite ends provided with eyes, one of which is reduced in thickness and the other slotted to receive the reduced portion for embracing the lock pin and operating crank by passing through the respective eyes thereof.

2. In a car coupler release rigging, a pin lifting link formed of two parts adapted to slide over each other, each respective part formed of two independent members, the opposite ends of which are provided with eyes, one of which is reduced in thickness and the other slotted to receive the reduced portion for embracing the lock pin and operating crank by passing through the respective eyes thereof.

MILLARD F. COX
